UNITED STATES PATENT OFFICE.

JACOB MAISH, OF WARSAW, INDIANA.

DOOR-CHECK.

SPECIFICATION forming part of Letters Patent No. 396,219, dated January 15, 1889.

Application filed September 11, 1888. Serial No. 285,122. (No model.)

To all whom it may concern:

Be it known that I, JACOB MAISH, of Warsaw, county of Kosciusko, and State of Indiana, have invented certain new and useful 5 Improvements in a Combined Door Stop, Catch, and Lock, of which the following is a full, clear, and exact description, that will enable others to make and use the same, reference being had to the accompanying drawings, forming a part of this specification.

This invention relates to that class of door stops and fasteners which are designed to hold a door in an open or closed position, either loosely or locked, as may be required.

15 The nature of the invention is such that it may also be used as a catch on articles of furniture—such as book-cases, wardrobes, and cupboards—having either single or double doors, for the purpose of loosely retaining the 20 same in a closed position.

Figure 1 is a plan of my improved device in practical use; Fig. 2, a transverse section in plane 2, Fig. 1; Fig. 3, a detail and plan of the member attached to and moving with the 25 door; Fig. 4, a plan of the stationary companion member provided with the locking feature; and Fig. 5, a view of the same, except the locking feature, which is removed.

In the drawings, A may represent the door, 30 to which the member B is rigidly attached, and A' the line of the floor or other stationary part supporting the companion member B'. The male member B consists of the head or irregular ring a, the foot-bar a', and the arms 35 a², connecting the head and foot-bar. This part of the stop is attached by means of the screws a³. The member B' is in the form of a double U-shaped spring made from a single strip of suitable metal, spring-steel being preferred. The ends of the spring forming the 40 member B' are secured some distance apart to the base-block b by means of the screws b', the outer sides, b², of the spring running parallel from the fastening-screws for some ways, 45 as shown, the central part of the strip of steel being bent or curved inward to form the inner sides, b³, or leaves of the spring and running back between the parallel outer sides. The inner part of the spring forming the mem-

ber B' is of a curvature corresponding to the 50 contour of the head of the member B, so as to clamp and loosely retain these parts in an engaged position. The base-block b is provided on the upper side with the raised inclined surface b⁴, which has a wedging action in connection with the member B, and brings the door into position to properly engage with the spring.

A locking attachment consisting of the bar C, and the latch D, hinged at one end to said 60 bar, is provided with the locking-pin d, which is adapted to engage with the lip or swell d', formed on the inner side of the ring-head, and thus secure the members B B' in a locked position, as shown in Figs. 1 and 2. The ends 65 of the bar C are secured in place by the screws holding the member B', as shown in Figs. 1 and 4. This locking attachment may be used or not or wholly dispensed with, as circumstances require.

The device is not alone applicable for holding doors in an open position, but may be used as a catch as well as a stop for closed doors, and especially screen-doors and the doors of different articles of furniture.

The base-block b, carrying the member B', is secured in place by screws d².

Having thus described my invention, what I claim, and desire to secure by Letters Patent, is—

1. In a door-check, the combination, with the member B, consisting of the head or ring a, the foot-bar a', and the arms a², of the member B', adapted to receive and loosely engage the companion member, and the base-block b, 85 provided with a raised inclined surface, b⁴, substantially as and for the purpose set forth.

2. In a door stop and lock, the combination, with the head or ring a, provided on the inner side with a lip or swell, of the bar C, the latch D, and the locking-pin d, engaging with said lip, substantially as and for the purpose set forth.

JACOB MAISH.
